INVENTOR
JOSEPH KAHN

UNITED STATES PATENT OFFICE.

JOSEPH KAHN, OF CHICAGO, ILLINOIS.

LOOSE-LEAF BINDER.

Application filed May 1, 1922. Serial No. 557,720.

To all whom it may concern:

Be it known that I, JOSEPH KAHN, a citizen of the United States, and a resident of the city of Chicago, in the county of Cook and State of Illinois, have invented certain new and useful Improvements in a Loose-Leaf Binder; and I do hereby declare that the following is a full, clear, and exact description of the same, reference being had to the accompanying drawings, and to the numerals of reference marked thereon, which form a part of this specification.

This invention relates to loose leaf binders in which the impaling posts are hingedly connected to the cover, and primarily consists of certain novel improvements in actuating and locking means for the shiftable hinge members which connect the impaling posts to the cover.

10 This application is a continuation in part of my application for loose leaf binder, Serial No. 428,182, filed December 4th, 1920, as to that matter common to both.

15 This invention comprises the novel mechanism and combination hereinafter described and more particularly pointed out and defined in the appended claims.

20 In the accompanying drawings, which illustrate a preferred embodiment of this invention, and in which similar reference numerals refer to similar features in the different views:

25 Figure 1 is a fragmentary plan view of the interior of the binder illustrating one position of the hinge members, with parts removed.

30 Figure 2 is a view similar to Fig. 1 showing the hinge members actuated for releasing the posts with posts removed.

35 Figure 3 is a fragmentary section on the line 3—3 of Figure 8.

40 Figure 4 is a fragmentary section through the back section of the binder.

45 Figure 5 is a view similar to Figure 4 illustrating an adjustable binder and sectional posts.

50 Figure 6 is a fragmentary plan view illustrating how the binder may be permanently locked.

55 Figure 7 is an elevational view partly in section of a leaf holding post.

60 Figure 8 is an interior plan view of the binder upon a reduced scale.

Figure 9 is a fragmentary section substantially on the line 9—9 of Figure 8 upon an enlarged scale.

Figure 10 is a fragmentary section on the line 10—10 of Figure 8 upon an enlarged scale.

Figure 11 is an interior plan view of a modified structure.

Figure 12 is a transverse section of the modified form.

Figure 13 is a fragmentary interior plan view of another modification.

Figure 14 is a cross sectional view of the binder shown in Figure 13.

Figure 15 is a section through the back of the binder showing the plan view of the leaves and posts extending therethrough.

Figure 16 is a cross section of a modified form of binder.

As shown on the drawings:

In referring to Figures 1 to 10, which illustrate one embodiment of this invention, the reference numerals 1 and 1^a represent the side covers of the binder which are hinged to the vertical clamping members 2 and 3 of the back of the binder, preferably by means of the fabric covering thereof, the member 3 being higher than the member 2. The clamping members 2 and 3 may be held in spaced relation by a rear member enclosed in suitable fabric that also covers the clamping members 2 and 3, or the clamping members may terminate in right angles overlapping parts for securing adjustability of the binder as shown in Figure 5. Where the adjustable binder is used, it will of course be necessary to use such sectional posts as are shown in Figure 5. However, these binder covers and sectional posts are old and well known in the art and form no part of this invention except in so far as they are modified or co-operate therewith.

According to this invention a plurality of spaced leaf holding posts 5, two in the present instance, span the rear portion of the binder. While these posts may be hingedly connected to both covers, the preferable construction consists in providing heads 6 (Figure 4) on one end of the posts and making the clamping members of unequal height and anchoring the headed end in the higher clamping member of the binder.

This may be accomplished by providing proper recesses in the upper margin of the clamping member 3 to receive said heads and extending apertures therethrough to receive said posts 5 in a horizontal axial plane above the top of the clamping member 2 as shown in Figure 4.

The opposite or projecting ends of the posts 5 are bifurcated, and links 7 are pivoted in these bifurcated portions. The free ends of said links are provided with eyes 8 and are adapted to pass between apertured lugs 10 projecting from a hinge plate 11 which is inset in the inner margin of the adjacent cover 1^a, the eyes 8 being adapted to be brought into registry with the apertures in the lugs, so that the hooked ends of the swingable hinge member 9 pivoted on the hinge plate 11 may pass through the apertures in lugs 10 and eyes 8 for hingedly connecting the posts to the said adjacent cover.

The hinge members 9 are adapted to be operated by actuators which are in the form of levers 12 pivoted intermediate their ends to the plate 11 adjacent said members 9. The inner or weight arms of said levers 12 extend over the hinge members 9, and the ends thereof are provided with downwardly extending lugs 13 (Fig. 3) adapted to engage the hinge members 9 and swing them into inoperative position, as shown in Figure 2, when the levers are swung in proper directions. The inner ends of said weight arms adjacent the pivot fulcrums are provided with cam portions 14 (Fig. 3), shown also in dotted lines in Figures 1 and 2, which are adapted to contact the outer sides of the hinge members and swing them into operative position in engagement with the lugs 10 and links 7 when said levers are swung from the positions shown in Fig. 2 to the positions shown in Fig. 1.

Mechanism has been provided for locking the impaling posts to the cover which is hinged thereto, and while this mechanism may take various forms, the illustrated mechanism comprises rotatable abutments 15 secured upon studs 16 which are provided with polygonal shaped heads or upper ends (Fig. 8) for receiving a wrench or the like whereby they may be rotated for rotating the abutments into the paths of the levers 12, as shown in Figure 6, to prevent further movement of said levers. Each abutment is normally retained in the position illustrated in Figures 1 and 2, in which a projecting tail piece 17 coacts with a stud projecting from the plate 11 for preventing improper rotation of the abutment. When the abutments are properly rotated into the path of the levers 12, they are arrested at a predetermined point by means of stops 18 which are in the form of pins or studs projecting from the plate 11, as shown in Figure 6, so that when the levers 12 are swung to disengage

the hinge members 9, they will strike the arrested abutments 15 and be held from further movement in the direction to release the hinge members. It will be noted that the stops 18 are so positioned that they pass between the lugs 13 and cam surfaces 14 of the levers during the operation of the levers to release the hinge members 9.

As previously mentioned, the plate 11 is inset in the inner margin of the cover so that the parts mounted thereon may be concealed by a cover 19 having side flanges resting upon the plate 11, the side flanges being provided with depending lugs or tongues 20 (Fig. 10) adapted to fit in sockets 21 formed in the marginal side edges of the plate 11, and the cover 19 being secured in position by a single screw 22 and the inner flange being cut away to accommodate the hinge members 9 and levers 12. As shown in Figure 8, the plate 19 is provided with apertures into which the polygonal heads of the studs 16 project so that they may be engaged by a wrench or the like, and the said plate 19 is shorter than the plate 11 leaving a space at each end into which the power arms or handle portions of the actuators 12 project so that they may be accessible for operation.

In Figures 11 and 12, a modification has been illustrated which differs from the previously described structure in the omission of the levers 12, the locking abutments 15 and the cover plate 19 and providing single hinge lugs on the plate 11, and the addition of guides 23 having stop lugs at each end to limit the swing of the hinge members 9 which normally rest between said stop lugs.

In the form shown in Figures 1 to 12, the leaves that are retained on the links 7 may shift longitudinally and become slightly offset with respect to the other leaves which are retained on the posts proper. In order to prevent this, medial posts 5^a may extend from the clamping member 3 for receiving the leaves and preventing the disarrangement or offsetting thereof.

In Figures 13, 14 and 15, I have illustrated a slightly modified form of binder in which cylindrical impaling posts are so constructed and arranged that relative longitudinal shifting of the leaves 24 is prevented. In this modified form, the end posts 25, which are secured to the clamping member 3 at their headed end, have their free ends mortised on their outwardly directed sides for receiving the hinge lugs 26 on the hinge plate 27 secured to the inner side of the cover 1^a. By mortising the end posts 25 upon their outwardly directed sides, the inwardly directed sides remain full, as shown in Fig. 15, and as these full or unmortised sides extend in opposite directions, they will combine to prevent the loose leaves 24 from being shifted in either longitudinal direc-

tion as is obvious from an inspection of Fig. 15. The mortised ends of the posts 25 and the lugs 26 have registering apertures for receiving the pivoted and swingable hinge hooks 9, as described in connection with the other forms.

In this form of the invention, a medial impaling post 28 extends from the clamping member 3 and is provided with a tenon upon its free end which fits between a pair of hinge lugs 29 on the plate 27. The tenon and hinge lugs 29 have registering apertures for receiving the pivoted and swingable hinge hook 9, which is adapted to be actuated by an actuating lever 12 similar to the one shown in Fig. 1. A shiftable abutment corresponding to the abutment 15 mounted upon a pin 16 serves to lock the actuator 12 as in the first described form, the parts being covered by a plate 30, only the handle of lever 12 and pin 16 being shown.

Fig. 16 illustrates a slightly different way of anchoring the impaling posts to the side 3^a of the binder. In this form, the impaling posts have conical heads fitting in countersunk apertures in a metal strip 3^b inset in the inner face of the clamping member 3^a and secured thereto, the clamping member 3^a being higher than the clamping member 2 as in the other forms so that the impaling posts lie in a plane above the clamping member 2 whereby their free ends may be hinged to the cover 1.

In the use of a binder involving this invention, loose leaves 24 properly punched are adapted to be retained on the impaling posts 5. When it is desired to add additional leaves to the binder the hinge members 9 are swung out of operative engagement with the posts 5, as previously described, whereby the clamping member 2 is disengaged from the posts 5 and may be shifted or swung outwardly or downwardly so that loose leaves may be readily impaled upon the posts. The binder is again assembled by bringing the hinge lugs on the plate 11 into registry with the links in the posts 5 and swinging the hinge members to engage the same as is obvious.

I am aware that numerous details of this invention may be varied through a wide range without departing from the principles of this invention, and I do not purpose limiting the patent granted otherwise than necessitated by the prior art.

I claim as my invention:

1. In a loose leaf binder having a pair of clamping members with covers hinged thereto, an impaling post anchored at one end in one of said clamping members, a hinge plate inset in the cover of the opposite clamping member, a swingable hinge member pivoted on said plate and adapted for effecting a hinge connection between the other end of said impaling post and said hinge plate, a

cover enclosing said hinge member, and an actuator for said hinge member pivoted to said plate and projecting beyond said cover.

2. In a loose leaf binder, a cover having a hollow chamber, impaling posts anchored to the side of the binder opposite said cover and means comprising a swingable hinge member in said chamber for hingedly connecting said posts to said cover, actuators extending beyond said chamber for operating said swingable members, and rotatable abutments adapted to be rotated in the paths of said actuators for locking the same in operative position.

3. In a loose leaf binder, the combination with the impaling posts, of swingable hinge members adapted for detachably hinging said posts to the cover, actuators for controlling said hinge members, and movable abutments for locking said actuators in operative hinged position.

4. In a loose leaf binder, the combination with impaling posts, of a cover having a hinge plate, a plurality of swingable hinge members pivoted to said plate and adapted for hingedly connecting said impaling posts to said cover, actuators pivoted to said hinge plate for operating said hinge members, and movable stops adapted for locking said actuators in operative position.

5. In a loose leaf binder, the combination with the impaling posts, of a cover having a hinge plate, swingable hinge members pivoted on said plate and adapted for hingedly connecting said posts to said plate, and actuators on said hinge plate for operating said hinge members.

6. In a loose leaf binder, the combination with an impaling post, of a cover having an inset hinge plate, a swingable hinge member pivoted to said plate and adapted for hingedly connecting said post to said plate, an actuator for said hinge member, and a movable stop for arresting said actuator.

7. In a loose leaf binder, a pair of clamping members of unequal height, a leaf impaling post, having one of its ends anchored adjacent the upper margin of the clamping member having the greatest height, covers hinged to said clamping members, and means hingedly connecting said impaling post to the cover of the clamping member having the lesser height.

8. In a loose leaf binder, a pair of clamping members of unequal height, covers hinged to said clamping members, an impaling post anchored at one end to the clamping member having the greatest height, a hinge plate on the cover of the clamping member having the least height, a swingable hinge member on said plate adapted for connecting said impaling post to said hinge plate, and an actuator for said hinge member.

9. In a loose leaf binder, the combination

with an impaling post, of a cover having a hinge plate, a swingable hinge member on said plate for hingedly connecting said impaling post to said plate, an actuator having 5 parts straddling said hinge member, and means for arresting said actuator to prevent operation of said hinge member.

10. In a loose leaf binder, a pair of clamping members, impaling posts each anchored 10 at one end to one of said clamping members, the free ends of said posts being mortised

upon their outwardly extending sides, and means for hinging the mortised ends to said binder.

In testimony whereof I have hereunto 15 subscribed my name in the presence of two subscribing witnesses.

JOSEPH KAHN.
